I claim the ornamental design for a toy space rocket, as shown and described.

DESCRIPTION

FIG. 1 is a top plan view of a toy space rocket showing my new design;

FIG. 2 is an elevational view of one side thereof; and,

FIG. 3 is a bottom plan view thereof.
The designs of the two sides of the article are symmetrical;
an elevational view of the side opposite FIG. 2 is a mirror image of FIG. 2.

The broken lines in the drawings illustrate portions of the article that are not part of my design.
